UNITED STATES PATENT OFFICE.

DANIEL W. McNEIL, OF CINCINNATI, OHIO, ASSIGNOR TO THE JOHN DOUGLAS COMPANY, OF CINCINNATI, OHIO, A CORPORATION OF OHIO.

SEAT-ACTUATED FLUSHING-VALVE.

No. 909,928.

Specification of Letters Patent.

Patented Jan. 19, 1909.

Application filed May 4, 1908. Serial No. 430,636.

To all whom it may concern:

Be it known that I, DANIEL W. McNEIL, a citizen of the United States of America, and resident of Cincinnati, county of Hamilton, 5 State of Ohio, have invented certain new and useful Improvements in Seat-Actuated Flushing-Valves, of which the following is a specification.

My invention relates to closet seats in 10 which the flush valve is released simultaneously with the release of the downward pressure upon the closet seat.

The object of my invention is a simple, durable and inconspicuous means of conveying 15 the motion of the mechanism which raises the seat, to the flushing valve. This object is attained by the means described in the specification and illustrated in the accompanying drawings, in which,—

20 Figure 1 is a side elevation of a closet provided with a flushing valve embodying my invention, the tank being shown broken out and the ends brought together to economize space. Fig. 2 is a sectional view of the ball 25 valve upon an enlarged scale. Fig. 3 is a perspective view of the shaft upon which the valve for actuating the jointed lever is secured. Fig. 4 is a perspective view of the jointed lever and of a part of the rod which 30 contacts the ball valve, one journal lug of the lever being shown broken away. Fig. 5 is a sectional view through the tank, the flushing connection, or flush pipe, and in elevation of the jointed lever, the contact rod and 35 the ball valve. Fig. 6 is a sectional view taken upon line α — α of Fig. 7. Fig. 7 is a side elevation of the journal plate, the journal rod, the spring, the bolts for mounting the journal rod upon the bowl, and the arm 40 for connecting the spring to the shaft which carries the actuating lug.

Referring to the parts: Ball valve, A, is seated against valve seat, a, in the bottom of the tank, B, the valve being guided to its 45 seat by its stem, a', passing through a suitably mounted guide arm, a². Ball valve, A, has a contact rod, A', the upper enlarged end of which is seated in the neck of the valve, and the lower end of which projects 50 down through a central opening, A², in the bottom of the valve. Valve stem, a', is screw-threaded into the upper end of the rod, A'. Valve seat, a, is formed at the upper end of a pipe, a³, secured in the bottom of the 55 tank. To the lower screw-threaded end of

the pipe, a³, a housing, C, is secured, which has a screw-threaded outlet, c', formed in alinement with pipe, a³. Into the opening, c', is screwed the pipe, d, which couples the housing to the rear of the bowl, D. Pipe, a³, and housing, C, have guide collars, a⁴, and a², respectively, in which the contact rod, e, is held in vertical alinement with the rod, A'. Rod, e, is reduced in width so as to form the shoulders, e', and e². 60

Housing, C, has a rearward extension, e³, in the walls of which rod, e³, is secured and actuating shaft, f, is journaled. A jointed lever for actuating the rod, e, is journaled upon the rod, e³. This lever consists of an 70 arm, E, whose divided end, e⁴, straddles the arm, e, so as to contact the shoulders, e', and e², the inner end of the arm, E, having a recess, e⁵, with a straight wall, e⁶. The other arm, E', of the jointed lever is journaled upon 75 rod, e³, within the recess, e⁵, and is formed with shoulders, e⁷, e⁸, the contact of which with the wall, e⁶, limits the rotation of the arm, E', upon the rod, e³. Upon the shaft, f, a contact lug, F, is secured in alinement 80 with the arm, e', and in a position such that the rotation of the shaft, f, will bring the lug, F, into contact with the arm, E'. The arm, E', is positioned upon the shaft, e³, such that when the shoulder, e⁸, contacts the wall, e⁶, the end of the arm, E', is in the path of the lug, F, and when the shoulder, e⁷, contacts the wall, e⁶, the end of the arm, E', is outside of the path of the lug, F. Thus, 85 when the contacting lug, F, is moved upward, it raises the arm, E', which, after the lug, F, has passed it, falls below the lug, F, so that a downward movement of the lug, F, will then cause the shoulder, e⁸, to bear 90 against the wall, e⁶, of the arm, E, and to rotate 95 the arm upward around its shaft, e³, to raise the rod, e, and bring it into contact with the rod, A', of the ball valve. The shaft, f, is coupled to the spring which raises the seat, in a manner such that when the seat is depressed, the lug, F, is raised, and when the pressure on the seat is released, the spring which raises it will rotate the shaft, f, in a direction so as to lower the lug, F.

I will now describe the details of this 105 mechanism: The journal plate, G, which is secured to the underside of the rear of the seat, g, is journaled upon a tube, g', which is mounted in collars, g², g³, which are formed integral with the bolts, g⁴, g⁵, which pass 110

downward through the rear of the bowl, D. In the collar, g^2 , a flat metal bar, g^6 , is held. The opposite end of the bar, g^6 , passes through a slot in the end of arm, K, one end, 5 k , of which is journaled upon the end of the tube, g' , and the opposite end of which is pivoted to a link, h' , whose opposite end is pivoted to an arm, f' , which is secured upon the end of the shaft, f . End, k , has a lug, 10 h^2 , which engages a lug, g^7 , upon the journal plate G. The action of the spring, g , is described in my pending application, which bears Serial Number 403,581. Spring, g^6 , is positioned such that when it is in its normal 15 position, it holds the seat, g , at its forward end from the bowl, and that when the seat, g , is depressed so as to touch the top of the bowl, the lug, g^7 , contacting the lug, h^2 , and rotating the arm, K, about the journal bar, 20 g' , will place the bar, g^6 , under tension, so that when the pressure on the seat, g , is released, the bar, g^6 , will return to its normal position and raise the seat.

The operation is as follows: When the 25 seat, g , is depressed, the arm, K, will be thrown upward at its rear end, will rotate the shaft, f , by means of the arms, h' , and f' , and will cause the contact lug, F, to rotate upward, so that its end stands above the end 30 of the arm, E', as illustrated in Fig. 5. As soon as the seat, g , is released from pressure, 35 spring, g^6 , will rotate the arm, K, so as to carry its rear end downward and rotate the shaft, f , through the arms, h , and f' , and cause the lug, F, to contact lever, E', and to 40 rotate the arm, E, so that its outer end, e^4 , raises the contact rod, e , and carries the ball valve, A, upward from its seat. As 45 soon as the lug, F, passes below the arm, E', it falls to its normal position, with the shoulder, e^8 , contacting the wall, e^6 , and the arm, E, of its own weight will fall to its normal position against the collar, e^2 . When the ball valve, A, is raised from its seat, it floats upward on the water, and will resume its seat when the water has passed out of the tank in the usual manner.

What I claim is:

1. In a water closet having a seat provided with a means for normally holding the seat raised from the bowl, the combination of a flush tank, a flush pipe, a valve seated against the end of the flush pipe, a contact device in the flush pipe below the valve and a means of connecting the contact device with the means for raising the seat and adapted to raise the contact device as the seat is raised. 50

2. In a water closet having a seat provided with a means for normally holding the seat raised from the bowl, the combination of a flush tank, a flush pipe, a valve seated against the end of the flush pipe, a lever journaled in the flush pipe, a contact device carried by the lever and a means of 60 actuating the lever to bring the contact device against the valve as the seat is raised. 65

3. In a seat-actuated flush valve the combination of a contact device normally resting in the flush pipe below the valve, a jointed lever journaled in the flush pipe and having one of its ends engaging the contact device, a rotatable shaft mounted in the flush pipe, means of coupling the shaft to the seat, an arm secured upon the shaft adjacent to the 70 other end of the lever and adapted to engage and raise the contact device when the seat is raised. 75

4. As a new article of manufacture, a hollow ball valve having a neck for engaging the valve stem and a perforation diametrically opposite the neck, an axial contact rod with its upper end seated in the neck and its lower end projecting through the perforation. 80

5. The combination of a rubber ball valve having upon one side a neck and diametrically opposite the neck a perforation, a contact rod having an enlarged end seated in the neck and projecting through the perforation and a stem engaging the enlarged end of the contact rod. 85 90
